Primary Examiner — Charles D Hanson(74) *Attorney, Agent, or Firm* — Joseph E. Maenner; Maenner & Associates, LLC**CLAIM**

The ornamental design for an intervertebral implant, as shown and described.

DESCRIPTION

FIG. 1 is a top perspective view of an ornamental design of a first embodiment of an intervertebral implant showing my new design.

FIG. 2 is a bottom perspective view thereof.

FIG. 3 is a front view thereof.

FIG. 4 is a rear side view thereof.

FIG. 5 is a top plan view thereof.

FIG. 6 is a bottom plan view thereof.

FIG. 7 is a left side view thereof; and,

FIG. 8 is a right side view thereof.

1 Claim, 7 Drawing Sheets---
